N. E. CLARK.
METAL WORKING MACHINE,
APPLICATION FILED DEC. 22, 1914.

Patented July 13, 1915.

UNITED STATES PATENT OFFICE.

NORRIS ELMORE CLARK, OF PLAINVILLE, CONNECTICUT.

METAL-WORKING MACHINE.

1,146,554.

Specification of Letters Patent.

Patented July 13, 1915.

Continuation in part of application Serial No. 741,376, filed January 11, 1913. This application filed December 22, 1914. Serial No. 878,604.

To all whom it may concern:

Be it known that I, NORRIS ELMORE CLARK, a citizen of the United States of America, and residing at Plainville, in the county of 5 Hartford and State of Connecticut, have invented new and useful Improvements in Metal-Working Machines, of which the following is a specification.

My invention relates particularly to the 10 step of "slitting" in the manufacture of what is commonly termed "expanded metal."

The main object is to provide simple mechanism for slitting regularly and accurately as set forth in my Patent #979,130.

15 Another object is to provide mechanism which is adapted to form strands of different widths.

Another object is to provide mechanism which can be used for slitting sections of a 20 sheet and leaving unslitted strips of greater or less width as desired.

Another object is to provide means for punching the unslitted sections of the sheet if desired.

25 Another object is to provide mechanism which can be cheaply made and readily set up and taken down and in which the "up keep" is small.

The invention contemplates the use of a 30 minimum number of rigid cutters rigidly held so as to avoid chattering, uneven work and consequent wear on the cutters. In the preferred form of the invention the cutting edges are formed on wedge-shaped blocks 35 and are so arranged that as the material to be cut is fed longitudinally step by step successive series of oppositely inclined rows of short slits in staggered arrangement are produced. These cutter blocks are reversible 40 and interchangeable both in the movable and in the stationary dies.

Figure 1, is a vertical longitudinal section of the preferred form of cutting tools adapted to be mounted in an ordinary reciprocating press preferably of high speed, with 45 short stroke and double roll feed. Fig. 2, is an end view and partial transverse vertical section of the cutting tools. Fig. 3, is a plan view of part of the lower die cutters, strippers 50 and lifter plates. Fig. 4, is a bottom view of a part of the upper movable dies. Fig. 5, is a perspective view showing one of the cutters

and the dogs for anchoring the ends of the cutter to the holder. Fig. 6 is a vertical sectional view of a fragment of the upper reciprocating holder with a punch for perforating between the slotted sections. 55

The stock is preferably fed into and out of the machine by suitable rolls (not shown) operating intermittently. The stationary 60 die cutters are carried by a bed holder 51 and the vertically movable tools or cutters are carried by the vertically reciprocating gate holder 50. The gate (not shown) is reciprocated in the usual manner common for 65 presses of this type.

The cutters 52, 52' in the preferred arrangement are laid out so as to slit a series of expandable sections such as 20, leaving the edge 21 and the connecting strips 22 unslotted. Each slotted section is made up of a series of rows of strands such as 23, 24 and 25, 26 inclined toward each other. The adjacent strands of the series 23, 24 are connected together at a plurality of points such 70 as 27 and 28 and the strands of the other series are similarly connected to each other in staggered arrangement so that the sections are extensible. The edges 21 and intermediate strips 22 obviously may be bent on 75 edge or corrugated if desired. Where the slits of the two converging series of a section do not meet in the center but leave a strip such as 32 as shown, these central strips may also be longitudinally grooved or corrugated 80 if desired either before or after slitting.

The slitting or cutting tools proper are carried by a gate holder 50 and a bed holder 51 and in the preferred form consist of a series of movable and stationary cutter 90 blocks which are all alike and similarly supported. As these tools are subjected to peculiar stresses in operation and tend to work loose and become distorted, it is necessary to construct them so that they can be accurately adjusted and rigidly supported so as 95 to avoid undue wear and consequent loss of time and material and expense in repair and adjustment, etc. Each cutter 52 is constructed as illustrated by the perspective 100 view of Fig. 5 of wedge-shape, flat on the top and bottom and inclined on the sides to the point 53. The sides are each provided with a series of grooves 54 which thus in-

terrupt the cutting edges 55 and 56 and afford a series of short cutting edges to correspond with the number of slits to be formed in each row of slits, in this case four. The 5 cross grooves 54' intersect the vertical grooves 54 so as to effect the cutting without tearing the metal.

The upper and lower holders each consists of a solid block with a number of wedge-shape recesses 57 for receiving the cutters. 10 Each cutter is held in place by two dogs. The toe dog 58 is cylindrical and fits in a cylindrically drilled hole 58' in the holder and is held down by a screw such as 59 which passes freely through the dog and 15 screws into a tapped hole 59' in the holder. This toe dog has a lug 60 which fits into a transverse slot 61 in the toe of the cutter. The heel of each cutter is held by a heel 20 dog 62 which has a flange 63 which fits in a slot 64 in the heel of the cutter. This dog is forced down toward the end of the cutter so as to force the cutter into its recess in the holder by means of a clamp bolt 65 which 25 passes through the flange 66 of the holder. A locking nut or clamping nut 67 is provided on this bolt. The dog 62 is clamped to the holder by a screw such as 68. This construction insures a proper centering and 30 clamping of the cutter and prevents it from working loose or being twisted out of place.

Between each two of the lower stationary die cutters may be arranged a lifting plate 35 supported on pins 71 which rest on but- 70 tons 72 each pressed upward by a spring 73 and screw 74. The tops of these lifter plates are normally on a level with or slightly above the tops of the stationary cutters.

The movable cutters are mounted ex- 40 actly like the lower cutters and are arranged over the lifter plates to fit between the lower cutters, and their vertical cutting edges co- 45 act, the grooves 54 of the upper and lower cutters being in alinement. A stripper plate 50 75 has a series of fingers 76 which are ar- 55 ranged somewhat above the tops of the lower die cutters.

The stock should be guided between the upper and lower dies for instance, by guides 50 such as 77 on each side. The lifter plates 70 force the metal stock upward after each stroke and free it from the lower die cutters while the stripper fingers 76 strip the material from the upper dies in case it ad- 55 heres to them in their retracting movement. The slitting of course slightly displaces parts of the strands from their original plane but the lifters can be adjusted to sub- 60 stantly flatten the stock after each stroke. A zig-zag row of short slits is formed at each stroke of the press. It will be noted 65 that the strands are formed by the rear edges of the upper cutters slicing past the front edges of the lower cutters. The stock is

therefore free to be fed forward even if the 65 cut strands are not lifted above the edges of the lower cutters after the cutting stroke. This also avoids wear on the cutters.

The length of the slits and consequently the length of the bonds between them de- 70 pends upon the size of the grooves 54 and 54' and may be varied by varying the width of the ends of the groove. By altering the length of the feed of the stock between slitting strokes, the width of the strands can be 75 readily varied. By leaving out some of the upper slitting cutters such as the one at the edge of the gate holder and the alternate in- 80 terior ones, broad unslotted strips will be left in the stock suitable for deep grooving or 85 folding to form deep ribs or beams. These broad unslotted strips may be perforated (for improving the bonding effect in the plaster or concrete) by means of punches such as 80 and dies such as 81 arranged in 85 line with the position of the upper slitter which is omitted (see Figs. 3 and 4). The stripper plate 75 may be perforated at 90 82 to admit the punch 80 and the die holder 51 may have a flaring discharge opening 83 for 95 the punchings.

It will be noted that each slitting cutter except the marginal lower cutters coöperates with two other cutters to form two oppo- 95 sitely inclined rows of slits. In case alter- 100 nate upper cutters are omitted, however, then each remaining upper cutter coöper- 105 ates with two of the lower cutters to form the inclined rows of slits in a section to be slotted and unslotted strips will be left where 100 the upper cutters are omitted. In case only the marginal lower slitting cutter is omitted an unslotted strip will be left whose width will equal the width of the strip 21 plus one-half the width of the slotted sec- 105 tion 20.

It will be obvious that different lengths of slits may be produced by simply sub- 110 stituting different slitting blocks with the appropriate edge grooves. The angle be- 115 tween the inclined rows of strands of course depends upon the angle of the cutting faces of the slitting blocks. The width of the end 53 of each upper cutter determines the width of the unslotted strip 32. So also the 115 width of the corresponding end of each lower cutter determines the width of the unslotted strip 22.

It should be understood that this process of slitting is equally well adapted to the slit- 120 ting of plain, flat sheets or sheets provided with ribs between the portions to be slitted. It should also be understood that the slitted product of these tools is flat or substantially flat without any material openings, and is 125 intended to be expanded or opened out in a subsequent step either in the same or in a separate machine.

This application is a continuation of my application #741,376 filed January 11, 1913 as to all matter herein shown and claimed except as to the punches 80 and dies 82 for 5 perforating the non-expansive portions of the stock.

What I claim is:—

1. In a metal working machine, a cutter holder having a series of V-shaped recesses, 10 wedge-shaped cutters located in said recesses and having interrupted cutting edges and slots in their front and rear edges respectively, a toe dog having a lug engaging in the slot in the toe of each cutter and a heel 15 dog having a flange engaging in the slot in the rear of each cutter.
2. In a metal working machine, a cutter holder having a series of V-shaped recesses, wedge-shaped cutters located in said recesses 20 and having interrupted cutting edges and slots in their front and rear edges respectively, a toe dog having a lug engaging in the slot in the toe of each cutter and a heel dog having a flange engaging in the slot in 25 the rear of each cutter and means for forcing said heel dog against said cutter.
3. In a metal working machine, a cutter holder having a series of V-shaped recesses with cylindrical recesses intersecting the 30 apices of the V's and a transverse recess at the base of the V's, wedge-shaped cutter blocks located in said V-shaped recesses, cylindrical toe dogs in said cylindrical recesses for holding the toes of said blocks 35 and heel dogs in said transverse recess for holding the heels of said blocks.
4. In a metal working machine, a cutter holder having a series of V-shaped recesses with vertical recesses intersecting the apices 40 of the V's and a transverse recess at the base of the V's, wedge-shaped cutter blocks located in said V-shaped recesses, toe dogs in said vertical recesses for holding the toes of said blocks, heel dogs in said transverse 45 recess for holding the heels of said blocks and screws for clamping said dogs to said holder.
5. In a metal working machine, a cutter holder having a series of V-shaped recesses 50 with recesses intersecting the apices of the V's and a transverse recess at the base of the V's, wedge-shaped cutter blocks located in said V-shaped recesses, toe dogs in said intersecting recesses for holding the toes of said blocks, heel dogs in said transverse recess for holding the heels of said blocks, screws for clamping said dogs to said holder and means for forcing said heel dogs toward 55 said cutter blocks.
6. In a metal working machine, a cutter holder having a series of V-shaped recesses with recesses intersecting the apices of the V's and a transverse recess at the base of the V's, wedge-shaped cutter blocks located 60
- in said V-shaped recesses, toe dogs in said 65 intersecting recesses for holding the toes of said blocks, heel dogs in said transverse recess for holding the heels of said blocks and spring pressed lifter plates arranged between said cutter blocks. 70
7. In a metal working machine, a cutter holder having a series of V-shaped recesses with recesses intersecting the apices of the V's and a transverse recess at the base of the V's, wedge-shaped cutter blocks located in 75 said V-shaped recesses, toe dogs in said intersecting recesses for holding the toes of said blocks, heel dogs in said transverse recess for holding the heels of said blocks, spring pressed lifter plates arranged between 80 said cutter blocks and a stripper plate having fingers projecting over said cutter blocks.
8. In a metal slitting machine, a holder, a set of wedge-shaped cutters carried thereby and having oppositely inclined cutting edges, a movable holder and a set of wedge-shaped cutters carried thereby and having oppositely inclined cutting edges, the cutting edges of one of said sets being interrupted for producing short slits in staggered 85 arrangement. 90
9. In a metal slitting machine, a stationary holder, a plurality of cutters secured thereto and each having a plurality of short 95 straight cutting edges in alignment, adjacent cutters having their cutting edges inclined in opposite directions to the line of feed, a movable holder, and cutters carried thereby coacting and interchangeable with 100 the stationary cutters.
10. In a metal slitting machine, a solid cutter block of materially greater width at one end than at the other and having a series of relatively short cutting edges along 105 opposite edges of the block in a common plane.
11. As an article of manufacture, a cutter for a slitting machine, said cutter comprising a solid block wider at one end than at 110 the other and with sides inclined toward each other forming oppositely inclined cutting edges on one face, said sides being grooved and one face having grooves intersecting the side grooves. 115
12. As an article of manufacture, a cutter for a slitting machine, said cutter comprising a solid block wider at one end than at the other and with sides inclined toward each other forming oppositely inclined cutting edges on one face, said sides being grooved. 120
13. In a metal slitting mechanism, a set of stationary cutters with oppositely inclined, substantially straight slitting edges 125 arranged in zig-zag outline across the direction of feed at the front of said cutters, and a movable set of cutters with oppositely

inclined substantially straight slitting edges arranged in similar zig-zag outline at the rear of said movable cutters, the edges of the cutters of one of said sets of cutters being interrupted and arranged to coact with the other set to form zig-zag rows of short slits inclined to the direction of feed and

leaving unslotted strips at the margins and along interior portions of the sheet.

NORRIS ELMORE CLARK.
